UNITED STATES PATENT OFFICE.

LYMAN O. HUDSON, OF STOCKTON, CALIFORNIA.

COMBINED PORTABLE PANTRY, DRESSER, AND SIDEBOARD.

SPECIFICATION forming part of Letters Patent No. 252,318, dated January 17, 1882.

Application filed May 11, 1881. (No model.)

To all whom it may concern:

Be it known that I, LYMAN O. HUDSON, a citizen of the United States, residing at Stockton, in the county of San Joaquin and State of California, have invented a certain new and useful Combined Portable Pantry, Dresser, and Sideboard; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to improvements in kitchen furniture, and is what I call a "kitchen-safe."

It consists in the combination, in one structure, of several different articles of furniture, 20 all arranged in convenient relation to each other.

Referring to the accompanying drawings, Figure 1 is a view of the entire article of furniture open. Fig. 2 is a detached view of the sideboard and holding segments thereof. Fig. 25 3 is a detached view of the bottom of the flour-bin.

A represents the upper or top pantry-section; B B, the side pantry-sections furnished 30 with suitable shelves. These three sections constitute the pantry proper, the doors of which may be furnished with openings covered with wire-gauze, preventing the access of flies and other winged insects, yet affording free ventilation.

35 C C are drawers for spoons and table-cutlery, located conveniently beneath the center of pantry-section A, and flanked on either hand by sections B B. A dresser, D, for dishes—40 having beneath it, and forming a part, spice-drawers a a—is located in the recess below the drawers C C.

The sideboard E, composed of a kneading-board, c, and sliding leaf d, hinged together, 45 is located above a flour-bin, G, and in front of dresser D, and, when closed, covers said flour-bin G and dresser D, and when open and in use, either as a sideboard or kneading-board, the said kneading-board c rests upon rubber 50 bumpers e e, inserted into segments F F, located in relation to either corner of sliding

leaf d, upon and at each end of the front edge of flour-bin G. The leaf d, carrying with it kneading-board c, when the latter rests upon the bumpers e e of segments F F, can be moved back and forth in suitable grooves or rests over the flour-bin G. The flour-bin G is provided with opening H in its bottom, furnished with plug or bung f, for conveniently cleaning the flour-bin G, the refuse contents of which are 60 dropped through opening H into a closet, K, beneath. The bottom of flour-bin G forms the roof or top of closet K, while the sides of one are a continuation of the other. The sideboard E may be removed out of the way, when required to fill or to clean the flour-bin G, by detaching the segments F F, which are screwed 65 upon edge of flour-bin G, permitting the sideboard E to be entirely drawn out and laid aside. Drawer M is located beneath either of 70 the side pantry-sections, B B, and may be used as a receptacle for table-linen, &c.

The entire structure is mounted upon supports L L L L, composed of short legs standing in and secured to metal or earthen saucers, 75 which latter may be filled with any fluid destructive to ants and prevent their obtaining access to the food upon the pantry-shelves.

By the above-described construction and combination of parts I claim to provide a very 80 compact and inexpensive article of kitchen-furniture, as therein are found a pantry or meat-safe, and a dresser for dishes, the cover for which dresser can be utilized as a sideboard, table, and kneading-board, while at all times it serves 85 as a cover for the flour-bin, and is readily removed when desired to fill or to cleanse the flour-bin; and, as will be seen, the flour-bin, with its improved bottom for the easy removal of refuse contents, is of great convenience to 90 the housewife. The locations of the different drawers for spoons, &c., table-linen, spices, &c., also of the closet beneath the flour-bin, I claim are chosen with strictest reference to 95 economy of space coupled with convenience of use.

By the use of wire-gauze doors for the pantry-sections and of the ant-protected leg-supports the entire structure is a perfect insect-proof kitchen-safe, its food contents, no matter how tempting, being out of the reach of those great household pests—flies and ants.

The advantages derived from the use of detachable segments F F, located as shown, and carrying bumpers *e*, are as follows: By screwing the segments to each corner of the front edge 5 of flour-bin G they prevent the sliding leaf *d* from slipping out of its place, yet by removing the bumpers *e* and unscrewing the segments the said leaf *d* can be readily slid out and removed from the cabinet. They also 10 serve as a rest or support for the kneading-board *c*. The process of kneading dough is materially aided by the spring imparted to the kneading-board by having the bumpers immediately beneath each outer corner of it. It will 15 thus be seen that the segments F F are utilized as follows: first, as holders of sliding board *d*; second, as rests for kneading-board *c* when it is in service as such, and, third, as foundations for the bumpers *e*. 20 Having described my invention, what I claim, and desire to secure by Letters Patent, is—

1. In a portable pantry-dresser and side-board, the center portion composed of a cabinet having a sliding leaf, *d*, held to its place 25 by segments F F, and having a kneading-board, *c*, hinged thereto at its rear edge, sliding beneath the dresser D and over the flour-bin G, drawers C C and a a, and closet K, the flour-bin G having openings in its bottom communicating with closet K, for the purpose of cleansing 30 the former of refuse contents, substantially as and for the purposes herein set forth.

2. The detachable segments F F, provided with bumpers *e* *e*, in combination with the dresser D, and arranged with relation to sliding leaf *d*, having hinged thereto at its rear edge the kneading-board *c*, substantially as 35 and for the purposes set forth.

3. In combination with the board E and bin G, the segments F F, provided with the bumpers *e* *e*, so that the latter may afford a rest for the kneading-board *c* when in use, while the segments F F prevent the sliding leaf *d* from slipping from its place except when desired by their removal, all operating substantially as 45 and in the manner herein described and set forth.

4. The combination of the sliding leaf *d* and kneading-board *c*, hinged to the rear of the leaf to form the sideboard E, with the bin G, 50 having segments F F, attached to each corner of front edge, and dresser D, whereby, when in service, said sideboard forms a cover for flour-bin G, and when the said board *c* is in a perpendicular position as a tight cover for said bin and for dresser D, substantially as herein shown and described.

5. A kitchen-safe having the pantry-sections A B B, drawers C C, dresser D, with spice drawers *a* *a*, kneading-board *c*, attached to sliding leaf *d*, forming sideboard E, segments F F, with bumpers *e* *e*, flour-bin G, with circular hole H in its bottom opening into closet K, and drawer M, for table-linen, in combination with supports L L L L, all constructed, arranged, and operated substantially as herein described and shown.

In testimony whereof I affix my signature in presence of two witnesses.

LYMAN O. HUDSON.
